(57) **CLAIM**

The ornamental design for a vaporizer for an aromatic odor neutralizer, as shown and described.

DESCRIPTION

This application is related to design application entitled dispenser cabinet for deodorant filed concurrently and a utility application entitled apparatus for dispensing an aromatic odor neutralizer filed May 24, 2007, all naming the same inventive entity given herein.

FIG. 1 is a perspective view showing a top, right side and front of a vaporizer for an aromatic odor neutralizer according to our new design;

FIG. 2 is a front view of the vaporizer for an aromatic odor neutralizer shown in FIG. 1;

FIG. 3 is a right side view of the vaporizer for an aromatic odor neutralizer shown in FIG. 1; and,

FIG. 4 is a rear view of the vaporizer for an aromatic odor neutralizer shown in FIG. 1.
